UNITED STATES PATENT OFFICE.

WILLIAM H. STEWART, OF BOSTON, MASSACHUSETTS.

SEWER-CLEANING APPARATUS.

No. 903,022.

Specification of Letters Patent.

Patented Nov. 3, 1908.

Application filed June 17, 1908. Serial No. 438,965.

To all whom it may concern:

Be it known that I, WILLIAM H. STEWART, of Boston, county of Suffolk, State of Massachusetts, have invented an Improvement in 5 Sewer-Cleaning Apparatus, of which the following is a specification.

This invention relates to sewer-cleaning apparatus of the type shown in Letters Patent #768,867 granted to me August 30, 1904, 10 and has for its object to improve the construction of the bucket, whereby it is made self-adjusting to better accommodate itself to the work to be performed, as for instance, to reduce its size when drawn into the pipe, 15 and to increase its capacity when drawn out; also to provide the self-adjusting bucket with means for holding the parts thereof separated in such manner that they may be moved toward each other; to improve the 20 construction of the cage whereby it is made self-adjusting to better accommodate itself to the work to be performed, as for instance, to reduce its size when drawn into the pipe, and to increase its size when drawn out; also 25 to provide a cage with a top runner and to provide yielding supporting means therefor; also to provide springs between the cage and bucket which act to press the bucket against the opposite side of the cage and hold it with 30 any degree of pressure, at least one of the springs being adjustable for this purpose; also to construct a discharging-device for the bucket and to provide means for operating it whereby the contents of the bucket may be 35 discharged; also to provide means for lifting the bucket so that after it has been moved along and has become filled it may be raised and then drawn out while in elevated position; also to provide means for locking the 40 bucket in its elevated position and for subsequently releasing it at different points to permit it to fall so that it may be again drawn along the pipe and filled.

Figure 1 is a side elevation of a sewer-cleaning apparatus embodying this invention. Fig. 2 is an enlarged longitudinal vertical section of the bucket shown in Fig. 1, the parts being in their normal open position. Fig. 3 is a view similar to Fig. 2, the parts being closed to reduce the size of the bucket. Fig. 4 is a side view of the bucket and cage. Fig. 5 is a plan view of the bucket-inclosing cage. Fig. 6 is a detail of the means for at-

taching the spring and the parts of the bucket. Fig. 7 is a transverse section of the bucket shown in Fig. 2, taken on the dotted line 7—7. Fig. 8 is a detail of the locking-device for holding the bucket in its elevated position. Fig. 9 is a detail showing modified means for raising the bucket.

The bucket consists of a lower part *a* and an upper part *b*, connected together loosely, preferably by sliding connections, to provide for movement of either with respect to the other in vertical planes, to thereby reduce 65 the size of the bucket when drawing it into the pipe and to increase its capacity when drawing it out. The lower part *a* consists of a sheet metal plate, made tapering from end to end, and curved transversely into semicircular form from end to end; and the upper part *b* consists of a flat plate made tapering from end to end corresponding to the taper given to the lower part, and having its sides bent downward to extend over the upwardly extended sides of the lower part. At 70 the small end of the bucket a closing plate *b'*, is attached to one of the parts, it being herein shown as attached to the upper part *b*, and extended downwardly, but in view of the employment of a discharging-device, to be hereinafter described, said closing plate may be omitted. The large end of the bucket is 75 open.

As herein shown, the lower part *a* has at its 80 forward end, at each side, an outwardly extended pin *a'*, and said pins enter vertical slots *b*² formed in the upwardly extended sides of the upper part *b*; and the upper part *b* has at its rear end, at each side, an inwardly 85 extended pin *b*³, and said pins enter vertical slots *a*² in the upper part. These pins may be riveted to the parts. In lieu of the pin and slot connections herein shown, other forms of loose connections may be employed.

The bucket, constructed as described or in any equivalent manner, is self-adjusting in that the parts thereof are free to approach each other to thereby reduce the size of the bucket when it is drawn into the pipe, and to 100 recede from each other and thereby increase the capacity of the bucket when drawn out. The two parts of the bucket are normally held separated, as shown in Figs. 1 and 2, hence it is reducible. A coiled spring *c* is 105 provided at the rear end of the bucket, the

ends of which are extended to form arms, which are connected respectively to the upper and lower parts of the bucket, the action of which is to separate the said parts. As 5 herein shown, the two arms respectively enter tubes c' , c' , which are rigidly secured to the upper and under sides of the bucket, and are held securely therein by set-screws or otherwise. The position of the spring may 10 be adjusted with respect to the bucket by moving its arms more or less into the tubes, and by such adjustment its action on the parts of the bucket may be varied. The arms of the spring may, however, be otherwise connected with the parts of the bucket. 15 In lieu of the employment of the spring c , for separating the two parts of the bucket, any other suitable means may be employed. The bucket is inclosed by a cage and is loosely 20 connected thereto, as for instance, the cage may have eyes d which engage the pins b^3 , which are extended outwardly for this purpose. The cage is made self-adjusting like 25 the bucket, that is to say, it is reducible, and, as herein shown, it comprises an upper part and a lower part, slidably connected together. The upper part comprises a pair of side bars or runners d' , d' , connected together at their ends, and at a point intermediate 30 their length they are bent to form the eye d which receives the pivot-pin. The lower part comprises a pair of side bars or runners d^3 , d^3 , each having at each end an upright portion d^4 , and said portions are extended up 35 through holes in the upper part, so that the two parts are thus slidably connected together. Movement of the parts in a direction away from each other is limited by nuts d^5 on the upper ends of the upright portions 40 d^4 . The two parts of the cage are normally held separated by springs d^6 , which encircle the upright portions d^4 , and bear at their upper ends against the upper part of the cage and at their lower ends against the lower part 45 thereof. By means of said springs the two parts of the cage are permitted to close as may be required when drawing the cage into and along the pipe. The cage has an eye d^7 , at each end, to which a cord, chain or equivalent d^8 is connected, and by suitable windlasses 50 said cords may be operated to move the cage along. Any suitable means may be employed for operating the cords so that the bucket may be drawn into the sewer or other pipe any desired distance and then 55 drawn out.

The cage has arranged on top of its upper part a yieldingly supported top runner n which is loosely connected by links n' with 60 said upper part, and said top runner is supported in elevated position by springs n^2 , encircling guide-pins n^3 , which are secured to and project downwardly from the runner and enter holes in the top part of the bucket. 65 One of said springs bears at its upper end

against the top of the bucket and the other spring bears at its upper end against the runner and at its lower end against an adjustable nut n^4 arranged on an externally screw-threaded post n^5 projecting upwardly from the top of the bucket which is made hollow to receive the lower end of the guide-pin n^3 . By turning said nut the tension of the spring may be varied so that it will exert a greater or less pressure on the bucket. Providing an 70 adjustable spring at the forward end on the bucket enables said forward end to be thrust down with greater or less pressure as may be required. As the top runner engages one side of the pipe the springs n^2 will act to force 75 the bucket downward or in a direction away from the top runner with considerable pressure, so that the forward end of the bucket will dig into the mud or other accumulation in the pipe and it is desirable to regulate the 80 force exerted, hence adjustment of the spring at the forward end of the bucket is provided. Normally the bucket is held pressed down against the lower part of the cage by the pressure, but this pressure is variable by the adjustment which is provided. 85

The bucket is herein shown as provided with a discharging device by which its contents may be discharged at any desired moment. One form of discharging-device is 90 herein shown for the purpose of illustrating my invention. It consists of a hoe-blade e , semicircular in shape, and of a size to approximately fit the rear end of the bucket, and extension plates e' , e' , loosely connected to it, a 95 supporting-bar e^2 also connected to it by means of which it may be operated. The extension plates e' , e' , are herein shown as curved longitudinally to conform to the transverse curvature of the lower part of the 100 bucket, and they each have a hook e^3 which extends through a suitable shaped hole in the hoe-blade e to connect it therewith loosely, so that as the hoe-blade is moved inward said extension plates will gradually rise 105 and finally occupy positions more or less at right angles to the hoe-blade, and as the hoe-blade is drawn out they will gradually fall until they occupy approximately vertical 110 positions. The supporting-bar e^2 of the hoe-blade is arranged horizontally in the upper part of the bucket, and is slidably connected therewith, it being arranged to slide in bearings provided on the under side of the top part. It is made longer than the bucket in 115 order that it may support the hoe-blade as the latter is moved in and out for the full length of the bucket, and hence extends beyond the bucket at each end. 120

Means are provided for moving the discharging-device, and, herein, cords e^4 are connected to the opposite ends of the sliding supporting-bar e^2 , which extend in opposite ways, and by pulling upon one or the other of these cords the bar may be moved in one 130

or the other direction to move the hoe-blade. These cords are or may be operated in substantially the same manner as the cords which are employed for moving the buckets.

5 Or one cord only may be employed, see Fig. 4, which is arranged to draw out the hoe-blade against action of a return spring e^8 , which is arranged on the end of the supporting-bar which projects from one end of the 13 bucket.

When digging out a sewer or other pipe it is often times desirable to lift the bucket as soon as it has become filled, instead of dragging it along on the bottom of the pipe after 15 it has become filled, and herein a cord g is extended from one to another manhole, which is held taut at the top part of the pipe and designed to serve as a runway for the bucket. A carriage g' is mounted on the runway 20 having wheels g^2 supported in brackets g^3 , arranged on the carriage, which engage and run along on the runway. To the under side of the carriage the bucket is suspended by means whereby it may be raised and 25 lowered with respect to the carriage. As herein shown, a cord h is fastened at one end to the carriage, as at h' , which passes under a pulley h^2 , arranged on top of the bucket, then under another pulley h^3 , also on top of the 30 bucket, then over the pulley h^4 , on the carriage, and is then carried to any suitable means by which it may be operated. Pulling upon this cord acts to lift the bucket and paying it out permits the bucket to fall by 35 gravity. The distance it is allowed to fall may be regulated by limiting the amount of cord which is paid out.

The bucket may have arranged on it a latch i , which, when in its elevated position 40 will engage a hook i' on the carriage, see Fig. 8, so as to lock the bucket in its elevated position.

After the bucket has been drawn along and has become filled it is raised and locked in 45 elevated position and is then drawn out and the contents of the bucket are discharged; then the bucket is returned, and on its return movement when it arrives at the proper place the hook on the carriage engages a block j on the runway and is moved to release the latch and permit the bucket to fall.

The block j is movable along on the runway to occupy different positions thereon as 50 may be required, and for the purpose of moving it along and for locking it on the runway in any position it may occupy a cam j' is pivoted to it which is movable into and out of engagement with the runway, said cam having an arm j^2 to which a cord j^3 is attached. Pulling upon the cord j^3 turns the 55 cam and disengages the runway and also moves along the block, and releasing the cord permits the cam to be restored into locking engagement with the raceway by means of a 60 spring j^4 , which is connected to its arm j^2 .

In lieu of providing the means shown in Fig. 1 for lifting the bucket an inclined frame or block, see Fig. 9, may be placed in the pipe, at the bottom, adjacent a manhole, and the bucket raised by being dragged up onto said 70 frame or block.

Having thus described my invention, what I claim as new and desire to secure by Letters Patent is:—

1. In a sewer-cleaning apparatus, a self-adjusting scoop bucket comprising an upper part and a lower part, loosely connected together and movable toward and from each other, substantially as described. 75

2. In a sewer-cleaning apparatus, a self-adjusting scoop bucket comprising an upper part and a lower part, slidably connected together, substantially as described. 80

3. In a sewer-cleaning apparatus, a self-adjusting scoop bucket comprising a transversely curved tapering lower part and a flat tapering upper part having downwardly extended side portions overlying the lower part, and means for connecting said parts loosely together, substantially as described. 85

4. In a sewer-cleaning apparatus, a self-adjusting scoop bucket comprising an upper part and a lower part loosely connected together and movable toward and from each other, and means for normally separating 90 said parts, substantially as described.

5. In a sewer-cleaning apparatus, a self-adjusting scoop bucket comprising an upper part and a lower part loosely connected together and a spring for yieldingly holding 100 said parts separated, substantially as described.

6. In a sewer-cleaning apparatus, a self-adjusting scoop bucket and a bucket-inclosing cage to which said bucket is pivotally 105 connected, adapted to be connected with means for moving it along, substantially as described.

7. In a sewer-cleaning apparatus, a self-adjusting scoop bucket comprising an upper 110 part and a lower part loosely connected together, and movable toward and from each other, and a self-adjusting bucket-inclosing cage to which said bucket is loosely connected comprising an upper part and a lower part 115 loosely connected together and movable toward and from each other, substantially as described.

8. In a sewer-cleaning apparatus, a self-adjusting scoop bucket comprising an upper 120 part and a lower part loosely connected together and movable toward and from each other, and a self-adjusting bucket-inclosing cage to which said bucket is loosely connected comprising an upper part and a lower part 125 loosely connected together and movable toward and from each other, and having means at its ends to which cords are connected by which it is moved along, substantially as described. 130

9. In a sewer-cleaning apparatus, a self-adjusting scoop bucket comprising an upper part and a lower part loosely connected together and movable toward and from each other, and a self-adjusting bucket-inclosing cage to which said bucket is loosely connected comprising an upper part and a lower part slidably connected together and movable toward and from each other, substantially as described.
10. In a sewer-cleaning apparatus, a self-adjusting scoop bucket comprising an upper part and a lower part loosely connected together and movable toward and from each other, and a self-adjusting bucket-inclosing cage to which said bucket is loosely connected comprising an upper part and a lower part loosely connected together and means for separating said parts, substantially as described.
11. In a sewer-cleaning apparatus, a self-adjusting scoop bucket comprising an upper part and a lower part loosely connected together and movable toward and from each other, and a self-adjusting bucket-inclosing cage to which said bucket is loosely connected comprising an upper part and a lower part loosely connected together, and springs for yieldingly separating said parts, substantially as described.
12. In a sewer-cleaning apparatus, a bucket, a bucket-inclosing cage having a top runner arranged above the bucket and connected at its ends to said cage, substantially as described.
13. In a sewer-cleaning apparatus, a bucket, a bucket-inclosing cage having a yieldingly supported top runner arranged above the bucket and connected at its ends to said cage, substantially as described.
14. In a sewer-cleaning apparatus, a bucket, a bucket-inclosing cage having a top runner connected at its ends to said cage and supporting-springs for said runner interposed between said runner and the bucket, substantially as described.
15. In a sewer-cleaning apparatus, a bucket, a cage to which said bucket is pivotally connected at one end, a top runner connected at its ends to said cage and springs interposed between said runner and bucket which act with a downward pressure on said bucket, substantially as described.
16. In a sewer-cleaning apparatus, a bucket, a cage to which said bucket is pivotally connected at one end, a top runner connected at its ends to said cage, and springs interposed between said runner and bucket which act with a downward pressure on said bucket, and means for adjusting one of said springs, substantially as described.
17. In a sewer-cleaning apparatus, a bucket, a bucket-inclosing cage, a top runner connected to said cage, means for connecting the bucket with said cage, and springs interposed between said runner and bucket for yieldingly supporting the runner and for pressing the bucket against the bottom of the cage, substantially as described.
18. In a sewer-cleaning apparatus, a bucket, a bucket-inclosing cage, a top runner connected to said cage, means for connecting the bucket with the cage, springs interposed between the runner and bucket, at points near the opposite ends thereof, for yieldingly supporting the runner and for pressing the bucket against the bottom of the cage, and means for adjusting the pressure of one of said springs, substantially as described.
19. In a sewer-cleaning apparatus, an expansible bucket, an expansible cage for the bucket, and means for connecting the bucket with the cage, substantially as described.
20. In a sewer-cleaning apparatus, a bucket adapted to be connected with means for moving it along and a discharging-device contained in the bucket and movable lengthwise thereof, substantially as described.
21. In a sewer-cleaning apparatus, a bucket adapted to be connected with means for moving it along, a discharging-device contained in the bucket, and means connected with the discharging device for moving it lengthwise the bucket in opposite ways, substantially as described.
22. In a sewer-cleaning apparatus, a bucket adapted to be connected with means for moving it along, of increasing dimensions from end to end, and an extensible discharging-device contained in the bucket and movable lengthwise thereof, substantially as described.
23. In a sewer-cleaning apparatus, a bucket adapted to be connected with means for moving it along, a discharging-blade contained therein and the sliding bar to which said blade is connected, having means for connecting it with means for sliding it, to move the blades lengthwise the bucket, substantially as described.
24. In a sewer-cleaning apparatus, a bucket adapted to be connected with means for moving it along, a discharging-blade contained therein having adjustable extensions and means for moving said blade, substantially as described.
25. In a sewer-cleaning apparatus, a carriage arranged on a runway, a bucket, means connecting said bucket with said carriage whereby it may be raised and lowered, a locking-device on the carriage for holding the bucket in its elevated position, means connected with the bucket for moving it and the carriage supporting it in opposite ways, a releasing-device for said locking-device, movably arranged on the runway, a locking-device for securing said releasing-device to

the runway at any position thereon it may occupy, and a cord connected with said locking-device for operating it to disengage the releasing-device from the runway and to draw said releasing-device along, substantially as described.

5 In testimony whereof, I have signed my

name to this specification, in the presence of two subscribing witnesses.
